FOLDING MACHINE AND METHOD OF
FOLDING

Philip L. O'Donnell, Norwood, Ohio

Application November 8, 1928, Serial No. 318,005

30 Claims. (CL 12—55)

My invention relates to folding machines, and particularly machines for folding French binding on shoes. My invention further relates to a novel method of treating the binding prior to its application on a shoe.

In my co-pending application Serial No. 253,700, filed February 11, 1928, I have disclosed a process for applying French binding to shoes which, broadly speaking, consists in providing a strip of binding having a partially coated band and securing this strip to a shoe by stitching an uncoated portion of the binding to the shoe and then heating the shoe and firmly pressing the coated portion against a surface of the shoe. Further in my co-pending application Serial No. 253,701, filed February 11, 1928, I have described a novel method of applying heat plastic adhesive in a narrow band to a strip of binding material. It is the object of my invention, as disclosed herein, to apply French binding, such as has been described in my latter application, in a particular way to a shoe and to heat the adhesive portion of the binding in a particular manner.

Broadly, it is the object of my invention to apply a blast of heated air to a strip of binding just prior to its application to a shoe. In the attempt to soften the heat plastic cement on a strip of binding having an uncoated portion of the binding stitched to the shoe, if the shoe itself is heated, there is danger of damage to the leather. If, on the other hand, parts of a folding machine are heated, the binding tends to stick. By the use of a blast of heated air, surprising results are obtained, and the binding can thereafter be applied very efficaciously.

The process of heating the adhesive portion of the binding with a blast of hot air, and a folding machine with which means for heating and discharging the heated blast in a particular manner is combined, constitute the subject matter of this invention.

Referring to the drawings in which I have illustrated a preferred type of folding machine showing my improvements:—

Figure 1 is a perspective view of a folding machine having a preferred form of air blast heater incorporated therewith.

Figure 2 is a sectional view of a preferred type of heater.

Figure 3 is a sectional view of a modified type of heater.

Figure 4 is an enlarged side elevation of the folding mechanism illustrated in Figure 1.

Figure 5 is a still further enlarged side elevation of the folding mechanism illustrated in Figure 1.

Figure 6 is a side elevation of a shoe upper having a strip of binding stitched but not cemented to the shoe.

Figure 6A is a plan view of a type of binding which I find adaptable for my new process.

The particular machine illustrated herein, which represents one type of folding machine with which I may incorporate my invention, is disclosed in the Glass Patents Nos. 1,281,555 and 1,281,556, of October 15, 1918. The machine has a supporting base 1 from which an arm 2, which houses the shuttle mechanism for advancing the work, extends. The work, which in this instance is a shoe upper, is placed on the end of the arm 2 and is fed along with the shuttle mechanism just as in a sewing machine. A guide pin 3 creases the French binding and guides it. The guide pin will usually be of sufficient length to bear against the tape or binding along its median line where there will not be any cement, so that there will be no tendency for the pin to cause the binding to stick to it. A forked folding finger 4, during the movement of the work through the machine, reciprocates back and forth and folds over the binding. A knurled roller 5, as is indicated in Figure 4, prevents the work from slipping.

There is a plate or anvil 6 which supports the bound edges of the work against the pressure of a hammer 7 which comes down on the work and presses the adhesive coated binding into firm engagement with the work.

For heating the adhesive coated band I have provided in the preferred modifications shown in Figures 1 and 2, a conduit 8 through which air is forced from a blower 9 which may be operated by an electric motor 10. There is a bushing 11 in the conduit 8 from which an air blast pipe 12 extends. The air blast pipe passes through an electrical resistance unit 13 provided with current as from the power feed lines 14 and 15. A casing 16 surrounds the resistance unit, and it may be insulated with wraps of insulative material such as is indicated at 17. The end of the blast pipe is curved downwardly, as indicated at 12a, and directed in such manner that just prior to the folding over operation of the machine the adhesive is warmed sufficiently so that it will stick when pressed firmly down.

In Figure 3 I have illustrated another type of air heater consisting of a casing 18 within which is a resistance unit 19 heated by the power feed lines 14a, 15a. The air conduit is indicated at 8a and the air blast pipe extending from the casing is indicated at 12b.

In Figures 4 to 6 I have shown a shoe upper

to which heat plastic adhesive binding 21 has been stitched being fed through the machine. In Figure 6 I have shown a plan view of a shoe upper 20 to which the adhesive binding 21 has 5 been stitched. In both figures the heat plastic band of cement is indicated at 21a.

The first step of attaching the French cord to the shoe upper produces a product such as is shown in Fig. 32 of British Patent 189,503 of 10 November 24, 1922; Fig. 5 of Williamson Patent 1,850,979, and in Fig. 10 of Evans Patent 1,618,754.

An operator then manually turns or bends the edge of the French cord, at one end of the combined upper and French cord, to a position extending beyond the edge of the upper, as shown 15 in Fig. 6 of Ridderstrom Patent 1,694,796 and feeds the upper and French cord into the folding machine and at that time, the hot air blast flows upon the adhesive. The folding machine folding finger 4 turns the French cord upwardly 20 at about a right angle to the upper 20 and then as the upper is progressively fed past the folding instrumentalities of the machine, the French cord is turned back over and is pressed down on the upper to produce a finished product such as is 25 shown in Fig. 4 of Ridderstrom Patent 1,694,796. In Fig. 4 hereof, the upper 20 and binding are shown bent downwardly from the table or work supporting part 2 of the French folder. In actual practice, the work is not bent into such a 30 position, however, the operator does first bend the margin of the French cord to effect an initial fold to substantially the position shown in Fig. 6 of Ridderstrom Patent 1,694,796. Then the hot air blast renders the adhesive tacky and the folding machine completes the job of folding as 35 previously explained and as particularly set forth in the appended claims of which claim 11 is typical.

40 Modifications in the machines with which I carry out my process will readily occur to those skilled in the art, as will also modifications in the particular steps of heating the binding with a hot blast of air or other gas, but insofar as the variation in process and apparatus does not depart from the broad principle involved, I consider such modifications within the scope of my invention.

Having thus described my invention, what I 50 claim as new and desire to secure by Letters Patent, is:—

1. The steps in the process of applying French binding to shoe parts which consists in heating with a blast of heated gas, a heat plastic portion 55 of a strip of binding which has been attached to a shoe part, and then folding over and attaching the portion thus rendered adhesive.

2. The steps in the process of applying French binding to shoe parts which consists in heating 60 with a blast of heated gas, a heat plastic portion of a strip of binding which has been attached to a shoe part, and then folding over and attaching the portion thus rendered adhesive, the heating blast being directed progressively to portions of the binding immediately prior to the application 65 thereof to the shoe.

3. In combination with the process of applying French binding having heat plastic adhesive thereon to shoe portions, the step which 70 consists in directing a blast of heated gas at the heat plastic portion of the binding shortly before its application to the shoe.

4. The steps in the process of applying partially adhesive coated binding to shoe parts which 75 consists in heating with hot gas directed upon

the coated portion of a strip of binding which has been attached to a shoe and then pressing down the coated portion to cause it to adhere to the shoe part.

5. In the process of applying French binding 5 to a shoe part which consists in coating a strip of binding with a band of heat plastic adhesive and then securing an uncoated portion of the binding to the shoe, the step which consists in directing a blast of heated gas against the coated 10 portion of the binding before its application to the shoe part.

6. In the process of applying French binding to a shoe part which consists in coating a strip 15 of binding with a band of heat plastic adhesive and then securing an uncoated portion of the binding to the shoe, the step which consists in directing a blast of heated gas against the coated portion of the binding and then folding over the coated portion and applying same to the shoe 20 part.

7. In combination with a French folding machine having folding mechanism, means for creating a blast of air, means for heating said blast, and means for directing said blast at a position 25 close to the folding mechanism in said machine.

8. In combination with a French folding machine having continuous folding mechanism, means for creating a blast of heated gas and means for directing said blast at a position close 30 to the folding mechanism in said machine.

9. In combination with a French folding machine having folding mechanism and a position 35 with relation thereto reached by work just prior to its arrival at said folding mechanism, means for directing a blast of heated gas toward said position.

10. In combination with a French folding machine having folding mechanism and a position 40 with relation thereto reached by work just prior to its arrival at said folding mechanism, and means for directing a blast of heated gas toward said position, said means operable continuously during the operation of said machine.

11. The method of folding a flexible piece of 45 work which comprises coating a margin thereof with a cement which is normally not sticky but may be rendered sticky by application of a softening agent, progressively bending the margin to form a fold, applying a stream of softening medium directly to the coating of cement on the bent margin, and thereafter progressively pressing the bent margin upon the body portion of the work.

12. The method of folding the margin of a 55 flexible piece of work over upon a face of the work which comprises coating a margin thereof with a cement which is normally not sticky but may be rendered sticky by the application of heat, progressively bending the margin to form a 60 fold, applying a gaseous heat stream directly to that face of the work against which the bent margin is to be pressed, and progressively pressing the margin upon the heated body portion of the work.

13. The method of treating a piece of sheet material which comprises attaching to the margin of the material a binding strip adapted to be folded over upon a face of the sheet material, said strip having upon part or all of one side thereof a 70 coating of cement which is normally not sticky but may be rendered sticky by the application of heat, progressively bending the strip about the edge of the sheet material to form a fold, applying a heated stream of gaseous medium di- 75

rectly to that face of the sheet material against which the strip is to be pressed, and progressively pressing the folded strip upon the margin of the sheet material.

5 14. A machine for operating upon a piece of work, which is provided, along its margin, with a band of cement adapted to be rendered sticky by the application of heat, having in combination a support for the work, means for pro-

10 gressively bending the margin to form a fold, means for applying a heated gaseous blast directly to that side of the bent margin which carries the cement, and means for progressively pressing the bent margin upon the body portion of the work.

15 15. A machine for operating upon a piece of work, which is provided, along its margin, with a band of cement adapted to be rendered sticky by the application of heat, having in combination a support for the work, means for pro-

20 gressively bending the margin into a position in which it may be pressed upon a face of the work, means for applying a hot gaseous blast directly to that face of the work against which the bent

25 margin is to be pressed, and means for progressively pressing the bent margin upon the body portion of the work.

30 16. The method of folding a flexible piece of work comprising a piece of material to which it attached a binding strip coated with a cement which is normally not sticky but may be rendered sticky by the application of heat, said method consisting in progressively bending the strip about the edge of the material, progressively applying a stream of heated gaseous medium directly to the coating of cement on the bent strip and progressively pressing the bent strip down upon the material.

35 17. The method of treating a piece of sheet material which comprises attaching to the margin of the material a binding strip adapted to be folded over upon a face of the sheet material, said material having upon part or all of one side thereof a coating of cement which is normally not sticky but which may be rendered sticky by the application of heat, progressively applying a stream of hot gaseous medium to the coated strip, and then progressively folding over the strip and pressing the strip upon the margin

40 of the sheet material.

45 18. The method of applying French binding to the edge of sheet material such as shoe uppers and the like which comprises stitching to the margin of the sheet material a French binding tape, the tape having on one face a coating of heat plastic adhesive, the other face of said tape initially lying completely on the outer face of the sheet material with an edge of the material and the tape substantially coincident, the stitching extending closely adjacent said coincident edges, then submitting the material with the tape stitched thereto to a French folding mechanism for progressively folding the tape about the edge of the sheet material whereby to dispose the free edge of the tape upon the opposite face of the sheet material, the adhesive side of the tape being then disposed upon said opposite face of the sheet material and progressively directing a heated gas to the adhesive face of the tape just prior to the actual folding of the tape by the folding mechanism.

50 19. In combination with a French folder of a source of heated gas under pressure and a nozzle for directing a blast of the heated gas imme-

diately adjacent and substantially within the line of operation of the folding mechanism.

5 20. That improvement in methods of securing a binding coated with meltable adhesive to the edge of a shoe upper, which consists in sewing one edge of the binding to the edge portion of the upper, blowing a hot gaseous fluid against the adhesively coated surface of said binding and thereby rendering said coating tacky, folding the binding over the edge of said upper and 10 against the margin thereof and, while said coating is still tacky, pressing said tacky surface against said margin.

15 21. That improvement in methods of securing a binding coated with meltable adhesive to the edge of a shoe upper, which consists in sewing one edge of the binding to the edge portion of the upper, blowing hot air against the adhesively coated surface of said binding and thereby rendering said coating tacky, feeding said binding 20 past the point of application of the hot air there-to, and during said feeding operation and while said adhesive is still tacky, folding the binding over the edge of said upper and pressing the tacky surface of the binding against the margin 25 of the upper.

25 22. That improvement in methods of securing a binding strip coated with a meltable adhesive to the edge of a shoe upper, which consists in fastening one edge of the binding to the margin 30 of the upper, blowing a hot gaseous fluid against the adhesive coating on the surface of said binding, feeding the edge of the shoe upper and the binding past the point at which the said fluid is directed against said coating and thereby pro-

35 gressively rendering said coating tacky, and pro-

40 gressively folding the binding over the edge of said upper and pressing it down upon the margin thereof as successive portions of the coating become tacky.

45 23. In a machine for folding a strip of edge binding material coated with a meltable adhesive about the edge of a shoe upper, or the like, comprising, in combination, folding devices for acting on said strip to fold it across the edge and to press it down upon the margin of the upper, means for feeding the work past said devices, and means for directing a current of hot gaseous fluid against the adhesive coating on said binding while it is being so fed to render said coat-

50 ing tacky for the operation thereon of said de-

55 vices.

24. In combination a series of cooperating elements for folding a tape about the edge of material, and means for applying a gaseous stream 55 of heat to the tape as such tape and material come under the influence of said cooperating elements.

60 25. In a device of the class described the combination of means for folding a tape longitudinally over the edge of material to which it is attached, guide means for directing the material and tape relative to said folding means, and means directionally projecting a hot gaseous stream for heating the tape as it passes over 65 the guide means.

65 26. The method of edge binding with tape comprising stitching the tape, which has been previously impregnated with heat plastic adhesive, adjacent an edge of material to be bound, then 70 feeding the material, with the tape thus attached, to suitable folding means, and directing a gaseous stream of heat to the tape prior to the action of the folding means on said tape and material.

27. The method of edge binding shoe uppers and the like comprising sewing to such an upper or the like a piece of binding tape impregnated with heat binding adhesive, then heating the tape with a stream of heated air to render the adhesive tacky then folding the tape about an edge of the upper, and pressing the adhesive tacky surface of the tape on the upper while the adhesive is still in a tacky state.
- 10 28. That improvement in methods of securing a binding coated with melttable adhesive to an article of work which consists in sewing one edge of the binding to the article, blowing a hot gaseous fluid against the adhesively coated surface of said binding and thereby rendering said coating tacky, and pressing said adhesively coated surface against said article while the adhesive is still tacky.
- 15 29. In a machine of the character described, the combination of means for folding a strip of sheet material coated with a melttable adhesive about an article of work, and means for forcing heated air from a source of supply against said coated surface to render said adhesive tacky preparatory to the action of said folding and pressing means on the strip. 5
30. The method of applying a nontacky adhesively coated French binding strip to a shoe upper which comprises the steps of stitching an edge of the strip to the edge of the upper, folding the strip with the coated side up, then directing a blast of softening medium to said turned coated side of the strip, and then pressing the surfaces together to effect adhesion thereof. 10 15

PHILIP L. O'DONNELL

CERTIFICATE OF CORRECTION.

Patent No. 2,018,866.

October 29, 1935.

PHILIP L. O'DONNELL.

It is hereby certified that error appears in the printed specification of the above numbered patent requiring correction as follows: Page 2, first column, line 75, claim 4, strike out the word "hot"; page 3, first column, line 30, claim 16, for "it" read is; and that the said Letters Patent should be read with these corrections therein that the same may conform to the record of the case in the Patent Office.

Signed and sealed this 21st day of January, A. D. 1936.

Leslie Frazer

(Seal)

Acting Commissioner of Patents.
